UNITED STATES PATENT OFFICE.

ANTON WEILER, OF SYRACUSE, NEW YORK.

DESIGN FOR A CORN-PARER.

SPECIFICATION forming part of Design No. 34,606, dated June 4, 1901.

Application filed April 22, 1901. Serial No. 57,031. Term of patent 7 years.

To all whom it may concern:

Be it known that I, ANTON WEILER, a citizen of the United States, and a resident of Syracuse, in the county of Onondaga, in the State of New York, have invented and produced a new and original Design for a Corn-Parer, of which the following, taken in connection with the accompanying drawings, is a full, clear, and exact description.

Figure 1 is a side view of a corn-parer, showing my design. Figs. 2 and 3 are plan views of the top and bottom of the same. Fig. 4 is a transverse section on line X X in Fig. 2 viewed in the direction of the arrow, and Fig.

5 is a longitudinal section on line Y Y of Fig. 2. As shown in the drawings, the leading or material features of my design consist of the prolonged tang or plate a, terminating at one end with a longitudinally-curved depressed

portion b, which has projecting upward from the longitudinal edges of the concaved side parallel flanges c c and has near its junction with the tang a a transverse slot d and is formed with an upward-projecting rib f across the extremity of said depressed portion. In this portion, central between the flanges c c and at a short distance back of the rib f, is a circular perforation e, substantially as shown.

Having described my invention, what I claim as new, and desire to secure by Letters Patent, is—

The design for a corn-parer as herein shown and described.

ANTON WEILER. [L. S.]
